10 Claims. (Cl. 57—58.95)

The present invention relates to a yarn controlling apparatus, and more particularly to apparatus for automatically guiding a yarn into the nip between a pair of cooperating transporting rollers. The apparatus is particularly advantageously used for transporting rollers disposed between the discharge opening of a spinning chamber and a winding roller which winds the yarn onto a bobbin while oscillating the yarn in axial direction whereby a cross wound yarn package is formed.

In spinning machines of this type, the transporting rollers withdraw the newly spun yarn from the spinning chamber and supply it to the winding roller. One of the transporting rollers is driven and extends across the discharge openings of several spinning chambers, while the second roller is a pressure roller, individually provided for each spinning chamber. It is customary to provide yarn guides between each spinning chamber and the transporting rollers, and between the transporting rollers and the winding roller so that the yarn is guided along a straight path from the discharge opening of the spinning chamber through the nip of the transporting rollers.

In the event that the yarn breaks, it is necessary to manually introduce the yarn between the transporting rollers, and to insert the same into the yarn guides.

Devices according to the prior art for introducing the yarn into the nip of the transporting rollers are only semi-automatic and require still a manual operation, while consisting of a great number of complicated parts which do not reliably operate. Furthermore, devices of the prior art are not suitable for spinning machines.

It is one object of the invention to overcome the disadvantages of the prior art, and to provide a yarn controlling apparatus by which a yarn is automatically placed in the nip of a pair of transporting rollers.

Another object of the invention is to provide a yarn controlling apparatus for automatically placing a yarn extending between a supply point and a winding roller into the nip of transporting rollers.

Another object of the invention is to use the oscillating motion of a yarn being cross wound by a winding roller, for inserting the yarn into the nip between a pair of transporting rollers.

Another object of the invention is to provide an automatic apparatus for placing a yarn which after repair of a yarn breakage extends between the discharge of a spinning machine and a winding roller, automatically in the nip of a pair of transporting rollers which withdraw the yarn from the spinning chamber and supply it to the winding roller.

Another object of the invention is to automatically place the yarn not only in the nip of a pair of transporting rollers, but also in a yarn guide.

With these objects in view, one embodiment of the invention comprises means for supplying a yarn at a supply point, for example the discharge opening of a rotary spinning chamber; winding roller means for winding up the yarn and for moving the yarn along an axially extending surface line between two end points, as is customary for winding rollers forming a cross wound package; and

2

a pair of first and second cooperating transporting rollers forming a nip and being located between the winding roller and the supply point.

In accordance with the invention, the first roller is disposed so that a yarn extending between the supply point and the surface line of the winding roller, rests on the peripheral surface of the first roller spaced from the nip of the rollers, and oscillates thereon since it is oscillated in axial direction by the winding roller. The first roller has on the peripheral surface thereof, a gripping means, preferably a notch, engaged by the oscillating yarn so that the gripping means of the turning roller moves the yarn into the nip between the transporting rollers which transport the yarn from the supply point to the winding roller.

In accordance with the invention, an imaginary tangential plane determined by the surface line of the winding roller, and by the supply point, the discharge opening of the spinning chamber, passes through the first roller, which preferably is a pressure roller cooperating with a driven roller. The pressure roller has a cylindrical periphery and an end face forming an annular edge with the cylindrical peripheral face of the roller and provided with a notch which constitutes the gripping means. When the yarn is located in one of the end positions extending between one end point of the surface line on the winding roller and the discharge opening of the spinning chamber, it crosses the plane of the end face and the annular edge of the pressure roller, so as to be engaged by the notch in the annular edge whereupon the yarn is carried into the nip between the rollers in the region of the annular edge, and during further oscillation moves further in axial direction into the nip, and at the same time into open yarn guides provided between the spinning chamber and the transporting rollers, and between the transporting rollers and the winding roller.

Preferably, the yarn guides are located in a plane which extends between the end face having the notch, and a transverse plane of symmetry of the pressure roller. One marginal tangent line of the imaginary tangential plane on the winding roller passes through the end face of the pressure roller and the other marginal tangent line passes through the cylindrical portion of the pressure roller.

The recesses of the open yarn guides are preferably located in a plane passing through the discharge opening of the spinning chamber, and the yarn guide between the transporting rollers and the winding roller, has on one side a guide face leading to its recess for guiding the oscillating yarn into the recess. An imaginary line between the other thread guide and one of the end points of the surface line on the winding roller, passes through the pressure roller in the region between its transverse axis and the gripping notch on its end face. This arrangement assures that the yarn which is angularly oscillated about the discharge opening of the spinning chamber, is not caught again by the rotating notch of the pressure roller and can move along the nip of the transporting rollers into both yarn guides.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a fragmentary schematic side elevation illustrating the winding apparatus of a spinning unit provided with the yarn control apparatus of the invention, in a working position during normal winding operations;

FIG. 2 is a fragmentary schematic front view of the apparatus shown in FIG. 1 in the same working position;

FIG. 3 is a fragmentary schematic side elevation illustrating the apparatus of FIG. 1 after a yarn breakage, and being partly diagrammatic; and

FIG. 4 is a fragmentary schematic front view illustrating the apparatus in the same condition as in FIG. 3, and being partly diagrammatic.

Referring now to the drawing, a spinning machine has a plurality of spinning units, each including a spinning chamber having a discharge opening 1. A driven transporting roller 4 extends along all discharge openings 1, which constitute supply points for yarn, only one discharge opening or supply point 1 being shown in the drawing. During normal operations, the yarn spun in the spinning chamber is discharged at supply point 1, guided in a recess of a front yarn guide 6 into the nip 8 of a pair of transporting rollers including drive roller 4 and pressure roller 5 which rotate in the direction indicated by arrows to withdraw the yarn from the spinning chamber and to transport the yarn P to a winding roller 2 of known construction which rotates to form a cross wound package 3 on a bobbin, and causes during rotation angular oscillation of the yarn P between the end positions P₁, P₂ and between the end points 19 and 20 on an axially extending surface line 12 on winding roller 2. This type of winding apparatus is well known, and not an object of the invention. As best seen in FIG. 2, during the normal operation of the spinning unit, the newly spun yarn withdrawn by cooperating rollers 5 and 4 moves in a plane perpendicularly to the axes of the rollers to the recess of yarn guide 7, which forms the apex of the angular oscillation of the yarn.

The spinning unit is provided with a sensing means, not shown, which responds to a yarn breakage to stop the feeding of fibers into the spinning chamber.

In the event of a yarn breakage, the spinning operation is stopped by the stop motion of the machine, and the broken end of the yarn is wound by winding roller 2 into the yarn package 3. In order to repair the yarn breakage, the operator unwinds a certain length of yarn P from the package 3 and places the free end of this yarn in the proximity of the discharge opening of the spinning chamber. Since the rotating spinning chamber produces suction by outwardly expelling air through small openings, the free yarn end is sucked into the spinning chamber and connected in the same with newly spun yarn so that the breakage is eliminated and winding operations may continue. However, in this condition of the apparatus, the yarn extends directly from the discharge opening 1 to any point of surface line 12 on the periphery of winding roller 2.

The repair of the yarn breakage is, of course, a standard procedure and well known to those skilled in the art.

In accordance with the invention, the yarn extending between discharge opening 1 and winding roller 2, is to be automatically placed in the nip 8 between the transporting rollers 4 and 5 so that the winding operations may continue in the position of FIG. 2.

In accordance with the invention, the pressure roller 5 is provided with a notch or corresponding gripping means 10 on the circular edge 9 between end face 15 and the cylindrical peripheral surface thereof. Furthermore, and referring to FIGS. 3 and 4, an imaginary plane 11 tangential to winding roller 2, and passing through supply point 1, surface line 12, and end points 19 and 20, intersects the pressure roller 5, as best seen in FIG. 3. The plane of intersection is preferably spaced from the axis of roller 5, three quarters of the radius r of the same.

The open yarn guide 6 is located between plane 11 and drive roller 4. A plane perpendicular to the axes of rollers 5 and 4 passes through supply point 1 and the recesses of thread guide 6 and 7, substantially equidistant from the end face 15 and the transverse plane of symmetry 13 of pressure roller 5, as best seen in FIG. 4.

The marginal lines 14 and 16 between supply point 1 and end points 19 and 20 may be considered projections of the yarn oscillated by winding roller after a yarn

breakage has been repaired, and before the yarn is placed in the nip of the transporting rollers 4 and 5. The marginal line 14 extends across end face 15 of pressure roller 5, so that a yarn in this position will rest on the peripheral portion of pressure roller 5 and across the annular edge 9. Consequently, during rotation of roller 5 the yarn in position 14 will be engaged by notch 10, and at the same time move inwardly about point 1 in axial direction of roller 5 and into notch 10. The yarn is carried around by notch 10 and placed in the nip of the transporting rollers 4, 5.

The other marginal line 16 passes through the cylindrical portion of pressure roller 5, so that a repaired yarn, which is not yet in the nip between the rollers, rests on the cylindrical peripheral surface of roller 5.

The rear guide 7 has a rounded off guide face 17 leading to the yarn guiding recess.

Another imaginary line 18 connecting the recess of yarn guide 6 with point 19, extends across pressure roller 5 in the region between end face 15 and transverse plane of symmetry 13.

As explained above, after a yarn breakage the free yarn end is introduced into the spinning chamber and extends between supply point 1 and any point of surface line 12 on winding roller 2 substantially in plane 11. When the machine is started, the yarn oscillates between positions 14 and 16, a yarn portion sliding at first on the peripheral surface of roller 5. The yarn oscillates until it engages the notch 10 substantially in the position 14 which pulls the yarn into the nip between rollers 5 and 4, the yarn continuing its oscillatory angular motion within the nip 8 until it engages the recess of yarn guide 6. Even in the outermost position passing through end point 19, represented by line 18, the yarn in the nip 8 of the rollers, does not cross the annular edge 9, and can consequently not be engaged by notch 10. Further oscillation of the yarn causes the same to slide along guide face 17 into the recess of yarn guide 7 so that the position of FIG. 2 is restored in which the yarn is oscillated by the winding roller 2 about the recess in yarn guide 7, and the transporting rollers 4, 5 transport the yarn through the yarn guide and toward winding roller 2.

Since the right hand end of roller 5 projects beyond the marginal line 16, it is not possible that the yarn passing to end point 20 slips over the right hand annular edge of roller 5 before being engaged by notch 10 during the initial oscillation between lines 14 and 16.

From the above description of an embodiment of the invention, it will become apparent that after a thread breakage has been repaired, the yarn is automatically placed in the nip between the transporting rollers and in the thread guides so that winding operations can be continued without requiring a manual operation for the threading of the yarn into the nip of the transporting rollers and into the thread guides.

It will be understood that each of the elements described above, or two or more together, may also find a useful application in other types of apparatus for inserting a yarn into the nip between a pair of transporting rollers differing from the types described above.

While the invention has been illustrated and described as embodied in an apparatus for inserting a yarn extending from a spinning chamber to a winding roller into the nip of transporting rollers after a yarn breakage, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and

are intended to be comprehended within the meaning and range of equivalence of the following claims.

What is claimed as new and desired to be secured by Letters Patent is:

1. Yarn controlling apparatus comprising, in combination, means for supplying a yarn at a supply point; winding roller means for winding up said yarn and for moving said yarn along an axially extending surface line between two end points; and a pair of first and second rotary transporting rollers forming a nip and located between said winding roller means and said supply point, said first roller being disposed so that a yarn extending between said supply point and said surface line rests on the peripheral surface thereof spaced from said nip, and angularly oscillates thereon while moving between said end points, said first roller having on said peripheral surface a gripping means engaged by said oscillating yarn during rotation of said first roller, and moving said yarn into the nip between said first and second rollers so that the same transport said yarn from said supply point to said winding roller means.

2. Yarn controlling apparatus according to claim 1 wherein said supply point and one of said end points are disposed so that yarn extending between the same crosses one end face of said first roller, said gripping means being located at an annular edge between said end face and said peripheral surface of said first roller.

3. Yarn controlling apparatus according to claim 2 wherein said gripping means includes a notch in said annular edge.

4. Yarn controlling apparatus according to claim 2 and including an open yarn guide located between said winding roller means and said pair of first and second rollers so that said yarn oscillating between said end points engages said open yarn guide whereby said yarn located in said nip between said first and second rollers is prevented from oscillation in said nip and oscillates between said yarn guide and said winding roller.

5. Yarn controlling apparatus according to claim 4 wherein said open yarn guide has a recess for guiding said yarn located substantially in a plane passing through said supply point perpendicularly to said surface line; wherein said end face and said gripping means are located on one side of said plane; and wherein said yarn guide has a guide face on said one side of said plane and leading to said recess for guiding said oscillating yarn into said recess.

6. In a spinning machine, in combination, a spinning means having a discharge opening for supplying a yarn at a supply point; a winding roller for winding up the spun yarn and for moving said yarn along an axially extending surface line between two end points; a pair of first and second rotary transporting rollers located between said winding roller and said supply point and forming a nip, said first roller having a peripheral surface and an end face forming with the same an annular edge formed with a notch; a front yarn guide located between said supply point and said supporting rollers; and a rear

yarn guide located between said transporting rollers and said winding roller; said first transporting roller being disposed so that a tangential plane on said winding roller passing through said surface line, said end points, and 5 said supply point, intersects said first roller, and so that a yarn located substantially in said plane and sliding on the peripheral surface of said first roller, crosses in a marginal position extending between said supply point and one of said end points said annular edge and is engaged by said notch during rotation of said first roller 10 to be positioned into the nip between said first and second roller so that during further oscillatory movement of said yarn toward a position extending from said supply point to the other end point, said yarn passes into the 15 recesses of said front and rear yarn guides while being located in said nip.

7. Apparatus according to claim 6 wherein said yarn guides are located in another plane extending between a transverse plane of symmetry of said first roller and said 20 annular edge of the same, said first roller being disposed in relation to said front yarn guide so that a yarn located in said nip and in said front yarn guide does not cross said annular edge so that engagement of said yarn by said notch is prevented after said yarn has engaged said 25 front yarn guide.

8. An apparatus according to claim 6 wherein said first roller has such a length and is disposed in such a manner that a yarn passing from said supply point substantially in said tangential plane to the other end point 30 of said surface line, does not cross the other end face of said first roller and oscillates on said peripheral surface of said first roller until engaged by said notch.

9. Apparatus according to claim 6 wherein said rear yarn guide has a guide face located in the region of said 35 annular edge having said notch so that a yarn oscillated in said nip is guided by said guide face into said rear yarn guide.

10. Apparatus according to claim 6 wherein an imaginary line in said tangential plane connecting said front 40 yarn guide with said end point, crosses said pressure roller in the region between a transverse plane of symmetry of the same and said end face so that said notch cannot engage said yarn after said front yarn guide has engaged the same.
